UNITED STATES PATENT OFFICE.

CARL DRUCKLIEB, OF NEW YORK, N. Y.

DESIGN FOR AN ICE-CREAM MOLD.

SPECIFICATION forming part of Design No. 16,840, dated August 3, 1886.

Application filed May 8, 1886. Serial No. 201,596. Term of patent 3½ years.

To all whom it may concern:

Be it known that I, CARL DRUCKLIEB, a resident of New York city, in the county and State of New York, have invented and produced a new and original Design for an Ice-Cream Mold, of which the following is a full, clear, and exact description, reference being made to the accompanying drawings, in which—

10 Figure 1 is a vertical section of my new ice-cream mold, the line *c c*, Fig. 3, indicating the plane of section. Fig. 2 is a vertical section of the same on the line *k k*, Fig. 3. Fig. 3 is a horizontal section of the same on the line *e k*, Fig. 1.

15 This invention relates to a new configuration of the internal chamber of an ice-cream mold; and it consists in parts that compose said mold so shaped that the same represent a chamber resembling leaves, out of which appears to grow a calla-like flower.

In the drawings, the letters A, B, and C represent the parts of the mold. Between these parts is shown the chamber or cavity D. The lower part, *a*, of this chamber or cavity D is 25 shaped to represent leaves, and the upper part, *b*, of this chamber is shaped in imitation of a calla-like flower.

I claim—

20 The design for the configuration of an ice-cream mold, the same consisting of the parts A, B, and C, the chamber D, the lower part, *a*, of which chamber represents leaves, and the upper part, *b*, of which chamber represents a flower, as shown.

CARL DRUCKLIEB.
